UNITED STATES PATENT OFFICE.

WALTER T. GODDARD, OF VICTOR, NEW YORK.

INSULATOR-CAP.

1,305,712.

Specification of Letters Patent. Patented June 3, 1919.

Application filed December 8, 1917. Serial No. 206,205.

To all whom it may concern:

Be it known that I, WALTER T. GODDARD, of Victor, in the county of Ontario and State of New York, have invented certain new and useful Improvements in Insulator-Caps; and I do hereby declare the following to be a full, clear, and exact description of the same, reference being had to the accompanying drawings, forming a part of this specification, and to the reference characters marked thereon.

My invention has for its chief purpose to provide an insulator cap that can be formed of sheet metal, and is specially applicable to the type of cap employed with high tension current insulating units and attached to porcelain or other insulating material, the cap acting as the immediate support for the insulating portion. A further purpose of the improvement is to provide a structure that can be economically manufactured within reasonable limitations, and which also possesses the strength and resisting qualities usually required by such a device. A more particular purpose of the invention is to permit making the entire structure of stamped sheet metal, and at the same time adequately protecting the interior of the cap so as to eliminate the possibility of moisture reaching the insulating material and finding lodgment there. To these and other ends the invention consists in certain improvements and combinations of parts, all as will be hereinafter more fully described, the novel features being pointed out in the claims at the end of the specification.

In the drawings:

Figure 1 is a side elevation of a cap constructed in accordance with my invention, with the connecting device attached;

Fig. 2 is a vertical sectional view on line 2^a—2^a of Fig. 1;

Fig. 3 is a horizontal sectional view on line 3^a—3^a of Fig. 1;

Fig. 4 is a sectional view taken vertically on line 4^a—4^a of Fig. 2;

Fig. 5 is a side elevation showing the application of the invention to a modified arrangement;

Fig. 6 is a vertical sectional view on line 6^a—6^a of Fig. 5;

Fig. 7 is a vertical sectional view on line 7^a—7^a of Fig. 6, with the connecting device attached to the cap, and

Fig. 8 is a plan view of the cap.

Similar reference characters throughout the several views indicate the same parts.

In the form shown in Figs. 1 to 4 inclusive, the cap includes an outer shell 1 that is formed from a sheet metal blank or plate 60 which is subjected to suitable stamping operations to form the side walls and top of the cap. The top is pressed upwardly at its central portion forming side walls or ears 2 which are further provided with 65 lateral openings 3, while 3^a is an opening at the extreme top to receive a connecting device. The side walls 2 are flanged inwardly surrounding the openings 3 as indicated by 70 4, providing a bearing for a pin 5 by which the connecting device or eye bolt 6 is attached to the cap. It will be observed that with an arrangement of this character formed by stamping operations, an opening 7 is produced in the top of the cap. To prevent moisture which enters through this opening from reaching the insulating material in the interior of the cap, I employ a protective member located beneath said opening and permanently attached to the 75 side walls of the outer shell 1.

This protective member is preferably in the form of an interior shell 8 having an upper portion 9 which extends across the under side of the top of the outer shell 1 85 and forms a complete inclosure under the opening 7. The shell 8 is permanently secured to the outer shell 1 and may be galvanized thereto or otherwise attached to accomplish the stated purpose. The inner 90 shell 8 thus has an intimate union with the outer shell 1 and forms a complete protection at the top, which effectively shields the interior against ingress of moisture. As the principal function of the inner shell is to 95 form a closure under the opening, the outer shell 1 is provided with drain passages 10 across its top to afford an outlet readily for any water or other liquids that might collect on the top of the inner shell 9.

Figs. 5 to 8 show the application of the invention to a modified arrangement adapted for a universal connection. The shell 11 is stamped outwardly, providing a bell-shaped socket 12 which is cut away at the 105 top at 13, and at the side as indicated by 14, to receive the enlarged end 15 of connecting bolt 16. The latter is held in place by a cotter pin 17, which engages the inner 110 end of the bolt 16 and prevents its removal.

The cotter pin 17 is inserted through the opening 18. 19 designates the inner shell formed of sheet metal, and galvanized or otherwise permanently attached to the outer shell 1 so as to have an intimate union therewith. The outer shell is cut away or recessed on its upper surface to provide drain passages 20 affording outlets for any moisture which collects upon the top of the inner shell 19, and the drain passages preferably terminate slightly beneath the uppermost surface of the inner shell, as shown in Figs. 4 and 7.

I claim as my invention:

- 15 1. An insulator cap consisting of an outer shell formed of sheet metal and having an opening in its top, and an inner shell permanently secured to the outer shell and sealing said opening in the latter so as to prevent access of moisture beyond the inner shell into the interior of the cap.
- 20 2. An insulator cap consisting of an outer shell formed of sheet metal and having an opening in its top, means above said opening for receiving a connecting device, and an inner shell of sheet metal galvanized to the side walls of the outer shell and extending entirely across the top so as to prevent access of moisture beyond the inner shell into the interior of the cap.

3. An insulator cap consisting of an outer shell formed of a sheet metal blank and having an opening in its top, a pair of ears above said opening stamped from the sheet metal blank for receiving a connecting device, and an inner shell of sheet metal galvanized to the side walls of the outer shell and extending entirely across the top so as to prevent access of moisture beyond said inner shell into the interior of the cap, the outer shell having a drain passage in its upper surface adjacent to the inner shell. 35 40

4. An insulator cap consisting of a shell formed of sheet metal and having an opening in its top, and a protective member located beneath said opening and permanently secured to the walls of the shell to seal the opening in the latter and prevent access of moisture beyond the protective member into the interior of the cap. 45

5. An insulator cap comprising a sheet metal outer shell with side and top walls, a supporting device stamped up from the top wall having an opening through the latter, and an imperforate inner shell secured within the outer shell so as to seal the opening in the top wall of the latter and prevent the entrance of moisture. 50 55

WALTER T. GODDARD.
